UNITED STATES PATENT OFFICE.

HARRY SCHATTMAN, OF NEW YORK, N. Y., ASSIGNOR TO A. L. WAGNER MFG. CO. INC.,
OF NEW YORK, N. Y.

DESIGN FOR A SALT AND PEPPER SHAKER OR ARTICLE OF SIMILAR NATURE.

Application filed May 21, 1927. Serial No. 22,122. Term of patent 3½ years.

To all whom it may concern:

Be it known that I, HARRY SCHATTMAN, a citizen of the United States, residing at New York, in the county and State of New York, have invented a new, original, and ornamental Design for a Salt and Pepper Shaker or Article of Similar Nature, of which the following is a specification, reference being had to the accompanying drawing, forming a part thereof.

The figure is a perspective view of a salt and pepper shaker showing my new design.

I claim:

The ornamental design for a salt and pepper shaker, or article of similar nature, as shown.

In testimony whereof I affix my signature.

HARRY SCHATTMAN.
